WALL PANEL OR SIMILAR ARTICLE

Howard C. Soehner, Louisville, Ky., assignor to
 The Mengel Company, Louisville, Ky., a corporation of New Jersey

Application June 11, 1949, Serial No. 3,214

Term of patent 14 years

(Cl. D13—1)

To all whom it may concern:

Be it known that I, Howard C. Soehner, a citizen of the United States, residing at Louisville, in the county of Jefferson and Commonwealth of Kentucky, have invented a new, original, and ornamental Design for a Wall Panel or Similar Article, of which the following is a specification, reference being had to the accompanying drawing, forming part thereof.

Fig. 1 is a front perspective view of a wall panel or similar article showing my new design;

Fig. 2 is a fragmentary vertical section of Fig. 1 taken along the line 2—2 on an enlarged scale; and

Fig. 3 is a fragmentary horizontal section taken along the line 3—3 of Fig. 1 on an enlarged scale.

I claim:

The ornamental design for a wall panel or similar article, substantially as shown.

HOWARD C. SOEHNER.
